UNITED STATES PATENT OFFICE.

EMIL C. KUESTER, OF OLNEY SPRINGS, COLORADO.

LOG-ROLLING DEVICE.

1,275,271.

Specification of Letters Patent. Patented Aug. 13, 1918.

Application filed February 18, 1917. Serial No. 149,063.

To all whom it may concern:

Be it known that I, EMIL C. KUESTER, a citizen of the United States, residing at Olney Springs, in the county of Crowley and State of Colorado, have invented certain new and useful Improvements in Log-Rolling Devices, of which the following is a specification.

This invention relates to a log turner or cant dog and has for an object the provision of an improved device of this nature, which may be easily and conveniently operated.

Another object of the invention is to movably mount the cant hook in the handle in order to facilitate a backward and forward movement of the handle without disengaging the cant hook from the log or other object with which it is engaged.

The above and other objects and advantages of this invention will be in part described, and in part understood from the following description of the present preferred embodiment, the same being illustrated in the accompanying drawings, in which—

Figure 1—is a side elevational view of my improved device.

Fig. 2—is an edge elevational view of the same and

Fig. 3—is a detail fragmentary sectional view of the device showing to advantage the cant hook.

Fig. 4 is a fragmentary view showing a modified form of the cant hook.

My improved device consists of a handle or stock 1 of ordinary construction, one end of which is provided with longitudinally extending recesses in its opposite sides, each of which receives one end of a supporting bar. These supporting bars 2 are secured to the handle 1 by means of rivets 3 or other suitable fastening means. The free ends of the supporting bars extend beyond the handle in spaced parallel relation.

The cant hook comprising an elongated body 4, one end 5 of which appreciably tapers, forming a foot, a segment 6 is formed on the lateral margin of the opposite end of said body and has its periphery formed to provide a rack bar 7. A portion of the lateral margin of the body, opposite said segment is extended to provide the bill of the hook as indicated at 8. The bill 8 is, arcuated downwardly in spaced relation to the foot 5, and terminates in an inwardly extending pointed end. From the above it

will be manifest that the body 4, segment 6 and bill 8 is an integral casting which is pivotally mounted between the extended portions of the bars 2, as indicated at 9.

A pawl 10 is pivotally mounted between the extended portions of said bars 2 in proximity to the handle 1. The free end of the pawl is thereby movable into the path of the rack 7. In this way movement of the handle 1, in one direction will bodily move the cant hook. Movement of the handle in an opposite direction will cause the pawl to pass over said rack 7 without taking effect on the latter.

In Fig. 4 a modification of the invention is shown, in which the bill 8 of the hook is pivotally connected to the body portion 4, as indicated at 11.

In use, it will of course be appreciated that the log or other object is first placed between the cant hook 8 and foot 5. By slightly tapering the latter engagement will be facilitated. The handle is then actuated as specified above, for rolling the log.

Having thus fully described my invention what I claim to be new and desire to secure by Letters Patent is:

1. A cant dog including a handle, a body portion pivoted thereto, the lower part of said body portion forming a foot, a toothed segment formed upon one edge thereof adjacent the top thereof, a dog secured to the body portion opposite the segment, and a driving pawl pivoted to the handle above said body portion for engagement with the toothed segment.

2. A cant dog including a handle, an elongated body portion pivoted to the handle, the lower part of said body portion forming a foot, an arcuate toothed segment formed upon the longitudinal edge of said body portion, the teeth on said segment extending to the top of the body portion, a dog secured to the opposite edge of the body portion a substantial distance from the top thereof, and a driving pawl pivoted to the handle above the body portion for engagement with the toothed segment.

3. A cant dog including a handle, a pair of spaced parallel arms secured to the end of said handle, a body portion pivoted intermediate its ends between said arms, the lower end of said body portion projecting beyond the lower ends of said arms to form a foot, an arcuate toothed segment formed upon the longitudinal edge of said body por-

tion, the teeth on said segment extending to the top of the body portion, a dog secured to the opposite edge of the body portion a substantial distance from the top thereof, 6 and a driving pawl pivoted to the handle above the body portion for engagement with the toothed segment.

In testimony whereof I affix my signature in presence of two witnesses,

EMIL C. KUESTER.
